Patented Mar. 16, 1915.

UNITED STATES PATENT OFFICE.

GOTTLIEB KLENK, OF DEFIANCE, OHIO, ASSIGNOR TO THE DEFIANCE PRESSED STEEL CO., OF DEFIANCE, OHIO, A CORPORATION OF OHIO.

METAL BOX.

1,131,935.

Specification of Letters Patent.

Patented Mar. 16, 1915.

Original application filed July 13, 1907, Serial No. 383,642. Divided and this application filed January 24, 1913. Serial No. 743,971.

To all whom it may concern:

Be it known that I, GOTTLIEB KLENK, a citizen of the United States, residing at Defiance, in the county of Defiance and State of Ohio, have invented certain new and useful Improvements in Metal Boxes, of which the following is a specification, reference being had therein to the accompanying drawings.

10 My invention relates to improvements in sheet metal boxes, relating more particularly to the corner structure of the bottom of the box, this application being a division of the application filed by me July 13, 1907, 15 Serial No. 383,642.

The objects of my invention are to provide a construction of this character in which the corner of the box and the portion of the bottom adjacent thereto are connected in a manner to mutually support each other, at the same time acting to reinforce the parts and stiffen them, thereby enabling a sheet metal box to be formed of relatively light material but capable of 25 withstanding the hardest uses, the box being capable of use for shipping purposes, etc.; additionally an object of the invention is to provide a structure which can be made of standard blanks readily assembled, and 30 which, when assembled, provides a box of maximum efficiency.

To these and other ends, the nature of which will be readily understood as the invention is hereinafter disclosed, my invention 35 consists in the improved construction and combination of parts, hereinafter fully described, illustrated in the accompanying drawings, and more particularly pointed out in the appended claims.

40 In the accompanying drawings, in which similar reference characters indicate similar parts in each of the views, Figure 1 is a perspective view of a box structure in accordance with the invention disclosed in the said parent application and which embodies the invention of the present application.

45 Fig. 2 is a bottom plan view of one of the corners of the box, showing an application of my invention. Fig. 3 is a fragmentary cross sectional view taken along the line 3—3 of Fig. 2. Fig. 4 is a fragmentary perspective view of a corner of the

box and illustrating the invention as applied. Fig. 5 is a detail of one of the bottom reinforcing strips in blank form.

55

As disclosed in the parent application, the box is formed with side and end sections, indicated respectively at 1 and 2, these sections being folded upon each other to provide substantial corner seams 3; the top edges of the sections are also beaded to inclose a reinforcing element 4. The bottom is indicated at 5, being formed with openings 6. The outer edges of the bottom are connected to the side and end sections by 60 being crimped thereto.

7 and 7^a designate reinforcing strips which are located below the bottom, these strips being adapted to form a portion of the crimp which connects the side and end 70 sections with the bottom, this construction being shown more particularly in Fig. 3.

The crimped portion comprising the three parts, the bottom, the reinforcing strip and the side or end sections as the case may be, 75 acts to provide a supporting flange 8, as exhibited in Fig. 3. The construction serves to provide not only an efficient binding for the parts, but, by reason of the particular form of the parts so connected, acts to prevent distortion of the edge of the box along the bottom without requiring the use of a special member to form a bead at this point. The said flange projects outward from the plane of the side or end sections and 80 therefore practically fends said sections during use, the vertical seams and the crimped portion, together with the reinforced bead at the top of the sections maintaining the same in approximately their 85 predetermined forms even under violent usage.

The reinforcing strips have the inner edges of their intermediate portions adapted, in connection with a reinforcing element 9, to form a bead or flange 10, the inner edges of the strips being rolled over the element, so that the latter acts to prevent distortion of the strips and therefore additionally reinforce the bottom of the box.

95

As shown more particularly in Figs. 1, 2 and 4, the strips 7 and 7^a have their ends of different configuration, the strip 7, indicated in blank form in Fig. 5, being pro-

100

vided with a projection 11, preferably at each end, said projection having parallel sides 11^a, an end 11^b and an inclined portion 11^c, the projection being of less width than 5 the width of the strip, with the outer edge 11^a alined with the outer edge of the strip, thus forming a cut-away portion on the inner edge of and at the end of the strip. This particular construction provides for 10 locating the reinforcing strip not only within the crimp of the section of the box below which it is positioned, but in addition also enters into and forms a part of the crimp provided by the sections of the box adjacent 15 to the section referred to. For instance, if the strip is located below a side section with its direction of length corresponding to the direction of length of such section, the ends of the strip will form a part of the crimp 20 which includes the opposite end sections, without, however, requiring the crimps of these adjacent sections to meet or overlap, said crimps, as shown in the drawings, being spaced apart with the spacing located 25 below the corner seam of the sections. By this particular arrangement, each reinforcing strip 7 not only acts as a support for the bottom, but also, through its connection with the crimp of the adjacent sections, serves to 30 hold such adjacent sections from spreading, thereby constituting an auxiliary to the reinforcing element 9 in retaining the bottom of the box in its predetermined form.

The strips 7^a differ from the strips 7 in 35 that the projections 11 are omitted, said strips 7^a simply having square edges and lying between the inner edges of opposing strips 7. As the strips 7 and 7^a are both formed of similar thickness of material, it 40 will be readily understood that this particular arrangement provides for a uniformity of the crimp which includes both forms of strips.

As shown in Fig. 3, the flange 10 is of 45 greater thickness than the crimp 8, thereby providing at the bottom of the box a projecting flange which is spaced from the outer edge of the box, so that it may act as a retaining element when two or more boxes 50 are placed one upon the other, said flange 10 being spaced from the outer edge of the box a distance sufficient to permit it to enter within the open top of a box on which it may be seated, the bottom of the crimp, in 55 such case, resting upon the upper edge of the under box and acting as an element to space the said top edge from the main face of the reinforcing strips, thus aiding in protecting the flat bottom portion along the edges of 60 the box.

The particular construction of the box as 65 an entirety is not claimed herein, that forming the subject matter of the parent application and of patents previously granted to me.

Having thus described my invention, what I claim as new is—

1. In a sheet metal box, adjacent vertical sections seamed together at their meeting edges, a bottom section crimped to said vertical sections, and a reinforcing strip for said bottom section having edges entering into the crimps of both of two adjacent vertical sections. 70

2. In a sheet metal box, adjacent vertical sections seamed together at their meeting edges, a bottom section crimped to said vertical sections, and a reinforcing strip for said bottom section having edges entering into the crimps of both of two adjacent vertical sections, said strip being located below the normal plane of the bottom section and having a downward projecting stacking bead formed at its inner edge. 75

3. In a sheet metal box, adjacent vertical sections seamed together at their meeting edges, a bottom section crimped to said vertical sections, and a reinforcing strip for said bottom section having edges entering into the crimps of both of two adjacent vertical sections, and a second reinforcing strip entering solely into the crimp of one of the last 80 said vertical sections.

4. In a sheet metal box, adjacent vertical sections seamed together at their meeting edges, a bottom section crimped to said vertical sections, and a reinforcing strip for said bottom section having edges entering into the crimps of both of two adjacent vertical sections, the crimped portions of the 95 strip being spaced apart with the spacing below the corner seam of the last said vertical sections. 100

5. In a sheet metal box, adjacent vertical sections seamed at their meeting edges, a bottom section crimped to both of two adjacent sections with the crimped portions spaced at the corner of the box below the seam, and a reinforcing strip beneath the bottom section with its edge parts crimped 110 with the bottom section to both of the said vertical sections, the said crimped portions being spaced at the corner of the box below the seam similarly to the the crimped portions of the bottom section. 115

6. In a sheet metal box, adjacent vertical sections seamed at their meeting edges, a bottom section crimped to both of two adjacent sections with the crimped portions spaced at the corner of the box below the seam, a reinforcing strip beneath the bottom section with its edge parts crimped with the bottom to both of the said vertical sections, the said crimped portions being spaced at the corner of the box below the seam similarly to the crimped portions of the bottom section and a second reinforcing strip having its direction of length extending at right angles to that of the first mentioned strip and having its end in juxtaposition to the inner edge of 125 130

- the end of said first mentioned strip, said second mentioned strip entering into the crimp of a single one of said vertical sections.
- 5 7. In a sheet metal box, adjacent vertical sections seamed together at their meeting edges, a bottom section crimped to said vertical sections, and a reinforcing strip for said bottom section having at each end 10 edges entering into the crimps of both of two adjacent vertical sections, the said strip having between its ends an inward projecting intermediate portion, the inner edges of which are formed into a downward projecting bead.
- 15 8. In a sheet metal box, adjacent vertical sections seamed together at their meeting edges, a bottom section crimped to said vertical sections, and a reinforcing strip for 20 said bottom section having at each end edges entering into the crimps of both of two adjacent vertical sections, the strip having an intermediate portion projecting inward between its ends and formed at its inner edge into a bead extending parallel with and spaced from the crimp of one of said sections, said bead being of a cross-sectional size to cause it to project below the plane of 25 said crimps.
9. In a sheet metal box, adjacent vertical sections seamed at their meeting edges, a bottom section crimped to both sections with the crimped portions spaced at the corner of the box below the seam, a reinforcing strip beneath the bottom section and having 35 a length and end configuration to cause it to enter at each end into the crimps of both of two adjacent vertical sections and provide the spacing between crimps in correspondence with that of the bottom section, 40 a second reinforcing strip having its direction of length extending at right angles to that of the first mentioned strip and having its end in juxtaposition to the inner edge of the end of said first mentioned strip, said 45 second mentioned strip entering into the crimp of a single one of said vertical sections, and a reinforcing element extending in parallelism with and spaced from the crimps of both strips, said element being 50 partially inclosed by the inner uncrimped edges of both strips.

In testimony whereof I affix my signature in the presence of two witnesses.
